(57) **CLAIM**

The ornamental design for a landscaping block, as shown and described.

DESCRIPTION

FIG. 1 is a front top perspective view of a landscaping block according to my new design;

FIG. 2 is a front bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side view thereof; and,

FIG. 8 is a right side view thereof.

The broken lines in FIGS. 1-5, 7 and 8 are included for the purpose of illustrating a portion of the landscaping block that forms no part of the claimed design.
